PACKAGING
Nicholas Marcalus, West Englewood, N.J.
(1 Market St., East Paterson, N.J.)
Filed July 18, 1963, Ser. No. 295,981
5 Claims. (Cl. 53—35)

My invention relates to packaging and more particularly to a method and means for packaging elongated tubular products.

In the packaging of tubular products, for example, rolls of gift wrapping paper, it is the practice, in many instances, to enclose the rolls in transparent containers, such as envelopes, bags, etc. in an endeavor to display to prospective users the appearance of the paper and designs thereon without the necessity of opening the containers to permit adequate viewing of the paper. Heretofore, so far as I am aware, the use of such transparent containers fails to clearly define and display the rolls of paper because of slack portions occurring in the containers transversely between the rolls and which slack portions are the result of loose packaging of the rolls within the containers. These slack portions, by reason of their concavities and undulations formed between the rolls, tend to produce somewhat translucent or frosted zones which serve to obscure, distort, becloud, and/or render indistinct the entire appearance of the paper, especially with respect to designs thereon, when viewed through the containers. Additionally and of importance is that when the rolls are thus encased within the containers, the resultant packages present a junky or untidy appearance thereby lessening sales appeal in many instances.

One of the objects of my invention is to provide a method for enveloping a transparent container about a plurality of sidewise disposed elongated objects by transversely shifting the objects within the container after insertion therein to tension the container about said objects thereby enabling the objects to be clearly displayed when viewed through the container and at the same time present a neat and attractive package thus enhancing their appearance.

Another object of my invention is to provide a method of packaging elongated tubular products such as rolls of gift wrapping paper wherein the rolls are inserted or loaded into a loosely fitting container and are laterally shifted relative to each other to insure a taut and tensioned condition of the container about the rolls to present a neat and attractive package and enable the paper to be clearly displayed and sharply defined when viewed through the container.

A further object of my invention is to provide means for treating a package of tubular products arranged in sidewise relation within a loose fitting transparent container and which means is effective for shifting the products within the container to create a tight fit of the container about the products to present a neat package and whereby the products may be more clearly viewed therein as compared to viewing through the container when loosely fitted about the products.

A still further object of my invention is to provide means for receiving a transparent container of loosely and laterally arranged tubular products and which means is equipped with product shifting means for relative shifting or positioning the products in a manner to tightly fit the products relative to each other and at the same time render the container taut about the products to present a neat package and whereby a clear view and sharp definition of the products may be obtained through the container.

An important object of my invention is to provide

2

means of the foregoing described character which is simple in construction, durable in use, effective in operation, economical in manufacture, and capable of employment in conjunction with auxiliary packaging devices without modification thereof to any appreciable extent.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

FIGURE 1 is a perspective view of a package wherein the products are disposed in their initial encased position;

FIGURE 2 is a top plan view of my invention in association with auxiliary devices;

FIGURE 3 is a sectional view taken on the line 3—3 of FIGURE 2;

FIGURE 4 is a detail sectional view taken on the line 4—4 of FIGURE 3 and illustrating the initial encased position of the products;

FIGURE 5 is a sectional view taken on the line 5—5 of FIGURE 3 and illustrating the final encased position of the products;

FIGURE 6 is a detail sectional view of the open end of the bag disposed in association with the air nozzle; and

FIGURE 7 is a perspective view of the package wherein the products are disposed in their final encased position.

In practicing my invention, as illustrated in the drawings, I employ a product positioning device or mechanism 5 having receiving and discharging ends 6 and 7, respectively. The device 5 is interposed between the discharge end 8 of a product delivering and encasing device or apparatus 9 and the receiving end 10 of a package sealing device 11.

The discharge end 8 of the apparatus 9 is equipped with a bag repository zone 12 containing a plurality of bags 13 for packaging tubular products such as rolls 14 of gift wrapping paper containing appropriate designs and/or being of various colors. The other end of the apparatus 9 is provided with a transversely arranged conveyor 15 for feeding the rolls 14 to the apparatus 9, a portion only of the conveyor being illustrated in FIGURES 2 and 3. The bags 13 are each provided with a closed or sealed leading end 16 arranged adjacent the receiving end 6 of the device 5 and an open trailing end 17 disposed in proximity to the conveyor 15 between the zone 12 and the conveyor 15. The apparatus 9 is equipped with a somewhat frustum-shaped air guide 18 in which is positioned an air nozzle 19 connected to a suitable air supply. The rolls 14 may each comprise a paper web wound about a cardboard core or the like.

As shown in FIGURE 6, the open end 17 of topmost bag is always presented to the air stream from the nozzle to effect opening of the bag, means not shown being employed for advancing the remaining bags upwardly as a bag is removed from the zone. When the bag is thus opened by air guided thereto by the air guide 18, the operator inserts a plurality of the rolls 14, for example, three, from the conveyor 15 into the bag and then detaches the closed end 16 of the bag from the apparatus 9. The closed ends 16 of the bags are detachably secured to the apparatus by a type of spring pressed means 20 of ordinary construction which permits the bags to be detached in successive order as they are loaded with the rolls. The rolls are inserted into the bag in a manner

wherein one of the rolls is superposed on and midway between the other rolls as clearly illustrated in the drawings. It is to be understood that the bags are constructed of a stable transparent plastic material, for example, Visking "q" film super clear, which is a non-stretchable polyethylene. The bags are of a predetermined width to effect a loose fitting about the rolls whereby slack occurs in the bags between the rolls as depicted in FIGURE 4. When the rolls are thus encased in a bag, the package 21 thus formed is fed by the operator to my product positioning mechanism 5.

My product or roll positioning mechanism 5 comprises a frame having spaced sides 22 connected together at their tops by a plate 23 and which sides are secured to the upper ends of legs 24 for supporting the frame above a floor or the like. Adjacent the front and rear ends 6 and 7, the frame has secured thereto bearings 25 in which are journaled front and rear shafts 26 and 27, respectively. The shafts 26 and 27 are equipped with rollers 28 over which are trained an endless conveyor belt 29 having an upper run 30 overlying the plate 23. The shaft 27 has keyed thereto a sprocket 31 driven by a chain 32 from a suitable source of power for rotating the rollers 28 in unison through the instrumentality and travel of the conveyor belt 29.

The frame is equipped with a pair of laterally disposed brackets 33 to which are connected spaced side members 34 of a tracking unit 35 disposed above the conveyor belt 29. The side members 34 have their ends equipped with bearings 36 in which are journaled front and rear shafts 37 and 38, respectively, with the rear shaft 38 having keyed thereto a gear 39 meshing with a similar gear 40 keyed to the shaft 27 whereby rotation of the shaft 38 is effected.

The shafts 37 and 38 have fixed thereto for rotation therewith front and rear pulleys 41 and 42, respectively, with each of said pulleys having spaced side flanges 43 between which are disposed an endless belt 44 trained about the pulleys and having a lower run 45 as illustrated in the drawings. The flanges 43 of the pulley 41 are of a greater diameter than the flanges of the pulley 42 for a purpose hereinafter made apparent. The axis of the shaft 37 is disposed a greater distance above the upper run 30 of the belt 29 than the axis of the shaft 38 to dispose the lower run 45 of the belt in a rearwardly and downwardly inclined plane relative to the substantially horizontal plane of the upper run 30 of the belt 29 as clearly illustrated in FIGURE 3 of the drawings.

The bearings in which the shafts 26 and 37 are mounted may be adjustable relative to the sides 22 of the frame and the members 34 of the unit 35 for adjusting the tension of the belts 30 and 44 by any suitable means, for instance, threaded rods 46 to the bearings and extending through lugs 47 carried on the sides 22 and members 34 and having threaded thereon nuts 48. The latter are adjustable on the rods 46 and against the lugs 47 to effect shifting of the bearings in a desired direction.

As the package 21, as disclosed in FIGURE 1, is fed on to the upper run 30 of the belt 29 by the operator, the leading end of the topmost roll within the package passes under the pulley 41 and between its flanges 43 whereby that portion of the bag 13 encasing the topmost roll is engaged by the lower run 45 of the belt 44. The belt 44 functions, in cooperation with the belt 29, to progressively force the topmost roll downwardly between the lowermost rolls as the package travels under the belt 44 due to the inclination of the lower run 45 thereof as shown in FIGURE 5 of the drawings.

It is to be understood that the topmost roll, as viewed in FIGURE 4, is disposed midway between the two lowermost rolls and which may be slightly spaced from each other. Therefore, when pressure is exerted on the topmost roll by the belt 44, the two lowermost rolls will be shifted laterally from each other thus permitting the topmost roll to be progressively forced downwardly between said lower-

most rolls to effect a tight fitting of the bag about the rolls as shown in FIGURE 5. Inasmuch as the rolls are substantially cylindrical in cross-section and possess some inherent degree of flexibility or resiliency, one or more of them may, during the insertion of the topmost roll between the lowermost rolls, assume a somewhat out-of-round or elliptical configuration in cross-section. However, the rolls will tend to assume their cylindricity or original shape as the package is advanced out of engagement with the flanges of the pulley 42 and thus maintain the taut condition of the bag or container about the rolls to present a package having a neat and trim appearance and which affords a clear inspection and definition of the rolls contained therein.

When the rolls are thus positioned in the package, as shown in FIGURE 5, the package is presented to the receiving end of the package sealing device 11 which seals the open end of the bag by a reciprocating sealing means 50, it being understood that the sealing device is of an ordinary construction and constitutes no part of the present invention per se. When the open end of the bag has thus been sealed, the package is ready for distribution and sale.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined solely to the use herein disclosed in connection therewith as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. Product positioning means, comprising a conveyor having a discharging end and adapted to receive a package of rolls of paper products loosely disposed within a transparent bag and initially arranged in a substantially triangular shaped group therein, and tracking means mounted over said conveyor and including a pair of spaced pulleys having flanges and an endless belt trained about said pulleys and inclined downwardly towards said discharging end, said flanges adapted to engage the bag adjacent one of said products for guiding said one product under said belt to enable said belt to cooperate with said conveyor to force said one product between a pair of the products during movement of the package under said belt from one end of the conveyor to the other whereby said bag is rendered taut about said products.

2. Product positioning means comprising a conveyor adapted to receive a package of cylindrical articles loosely disposed within a container and initially in a substantially pyramid shape therein, and tracking means mounted over the conveyor and including an endless device inclined downwardly toward one end portion of the conveyor, and means for guiding said endless device including a pulley having flanges arranged to engage and bear upon the container in guided relation with the topmost article for guiding said article under the endless device to force said topmost article between a pair of articles during movement of the container along the conveyor.

3. Product positioning means comprising an elongated conveyor having a discharge end and adapted to receive thereon rolls of products loosely enclosed within a container and with a larger and smaller number of said rolls being initially arranged in proximus and distal relation to said conveyor, respectively, and elongated tracking means mounted over said conveyor and provided with spaced lateral guide members at opposite ends of said

means and an endless flexible device disposed between the guide members at said ends and with said flexible device inclined downwardly toward said discharge end, said guide members having means for engaging the container adjacent said smaller number of rolls and guiding the latter under said flexible device to enable said flexible device to cooperate with said conveyor to force said smaller number of rolls into transverse alignment with said larger number of said rolls during movement of the container under said flexible device from one end of the conveyor to the other whereby said container is rendered taut about said rolls by said transverse alignment.

4. A method of packaging a plurality of cylindrical articles, comprising moving the articles lengthwise in a pyramid shaped assembly within a loosely fitting container, moving the container bodily lengthwise along a path, and progressively applying downward pressure along the length of the topmost article in the container during movement of the articles along said path and forcing all of the articles in said container into a common plane.

5. A method of packaging a plurality of elongated rolls of wrapping paper comprising inserting the rolls lengthwise in a pyramid shape within a transparent bag having a circumferential area sufficient to receive the plurality of rolls loosely in pyramid shape and to tautly encompass the rolls when rearranged in a common plane, moving the container and articles bodily lengthwise along a path, and progressively applying downward pressure along the length of the topmost roll in the container during movement of the rolls along said path and thereby forcing all of the rolls into a common plane.
